UNITED STATES PATENT OFFICE.

AGNES KINDER, OF SEATTLE, WASHINGTON.

DESIGN FOR A CLOTHES RACK AND STAND.

53,451.

Specification for Design.

Patented June 17, 1919.

Application filed February 28, 1919. Serial No. 279,893. Term of patent 14 years.

To all whom it may concern:

Be it known that I, AGNES KINDER, a citizen of the United States of America, residing at Seattle, in the county of King and State of Washington, have invented a new, original, and ornamental Design for a Clothes Rack and Stand, of which the following is a specification, reference being had therein to the accompanying drawings.

Figure 1 is an inverted plan view of the

clothes rack and stand, showing my new design.

Fig. 2 is a view in side elevation.

Fig. 3 is a top plan view.

I claim:

The ornamental design for a clothes rack and stand, as shown.

In testimony whereof I hereunto affix my signature.

AGNES KINDER.
